UNITED STATES PATENT OFFICE.

WALTER N. VANCE, OF CHICAGO HEIGHTS, ILLINOIS, ASSIGNOR TO DURAND STEEL LOCKER COMPANY, OF CHICAGO, ILLINOIS, A CORPORATION OF ILLINOIS.

HINGE.

Application filed October 25, 1920. Serial No. 419,160.

To all whom it may concern:

Be it known that I, WALTER N. VANCE, a citizen of the United States, residing in Chicago Heights, in the county of Cook and State of Illinois, have invented a new and useful Improvement in Hinges, of which the following is a specification.

This invention relates in general to hinges for lockers and other doors, and has for its 10 principal object the provision of a hinge of light flat metal construction of considerable strength and adapted to limit opening movement of the door to desired amount, as for example, approximately 100 degrees.

15 The invention contemplates, in this regard, the provision of a hinge limiting the opening movement of the door, and this without the provision of heavy cast or other parts, adding to the cost of the construction.

20 The invention also contemplates the provision of a limiting hinge member which may be merely stamped from metal of suitable gauge and readily assembled in the structure without preformation other than 25 the mere stamping operation.

Other objects and advantages of the invention will be apparent as it is better understood from the following description when considered in connection with the 30 accompanying drawing illustrating a preferred embodiment thereof.

Referring to the drawings,

Figure 1 is an enlarged partial perspective view of a hinge connection embodying 35 my present invention;

Fig. 2 is a section taken on the line 2—2 in Fig. 3; and

Fig. 3 is a section taken on the line 3—3 in Fig. 1.

40 For the purpose of illustrating my invention, I have shown a portion of locker assemblage, comprising a corner upright 11 of angle iron construction, a portion of the side wall 12 of sheet metal, and a portion 45 of a door 13 of the same material. This door is provided at its hinge end with an inwardly extending flange 14 and with two rivet-receiving openings 15 and 16 to permit securing of the hinge. The angle iron 50 or jamb 11 is slotted as indicated at 17 and is provided with apertures 18 and 19 above and beneath the slot.

The hinge member proper comprises a flat piece of sheet metal 21 of suitable gauge.

55 This hinge member is adapted to be ar-

ranged with its flat edge 22 against the outer face of the door and two rivets 23 and 24 extending through the openings 15 and 16, are upset to hold the hinge member to the door. The hinge member has a portion 25 adapted to be disposed in the slot 17, and just outwardly of this portion the hinge member is perforated at 26 to receive the body of a staple 27, having its ends 28 inserted through the apertures 18 and 19 and riveted over as indicated at 29.

A washer 31 is preferably also positioned on the staple 27 and beneath the hinge member 21 to provide a smooth supporting bearing of the hinge member in turning. The 70 edge of the hinge member rearwardly of the opening 26 is of arcuate shape as indicated at 31' to permit the easy opening of the door and movement of the hinge member in the slot.

In order that this door opening movement may be limited to desired amount I provide a shoulder 32 on the hinge member and extending out therefrom. This shoulder is adapted to engage the jamb or 80 angle iron 11 when the door has slightly past 90 degrees, thus preventing the locker door from swinging around in the way of the next adjacent locker. The shoulder 32 is provided by merely widening the flat 85 hinge member 21 and without upsetting it or requiring any additional operation in its construction. The entire hinge member may be stamped out at a single die operation, and the assembling requires merely threading the washer and hinge member on the staple and inserting the rivets 23—24 through the door, staple ends through the jamb, and riveting over the parts extending within the locker.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

100 I claim:

1. In a sheet metal locker and the like, a jamb member, a door, a hinge member fast to the door and having a part extending out into a slot of said jamb, and a staple 110

passing through said hinge member and into the jamb at opposite sides of said slot, said hinge member having a protruding shoulder for engaging the outer side of said jamb to limit the door opening movement.

2. In a sheet metal locker and the like, a slotted door jamb, a door, a hinge member secured for opening and closing movement in the slot of the jamb and having a shoulder 10 engaging the edge of said slot for limiting the door movement.

3. In a sheet metal locker and the like, a structural metal door jamb slotted to receive a hinge member, a sheet metal door, and 15 hinge member engaging said door and arranged flatwise in said slot and having a shoulder for engaging the jamb to limit opening movement of the door.

4. In a sheet metal locker and the like, a slotted door jamb, a door, a flat strip of metal 20 arranged flatwise in said slot and secured in

the outer face of said door and having a shoulder engaging the jamb to limit opening movement of the door.

5. In a sheet metal locker and the like, a slotted door jamb, a door, a hinge member comprising a flat strip of metal arranged flatwise in said slot and secured in the outer face of said door and having a shoulder engaging the jamb to limit opening movement 30 of the door, and a staple passing through said hinge member and said jamb.

6. In a sheet metal locker and the like, a door jamb, a door, a flat strip of metal arranged flatwise horizontally and secured to 35 the outer face of the door, a staple passed through said strip and engaged in the jamb, said strip of metal acting as a hinge member, and having a shoulder engaging the jamb to limit the opening movement.

WALTER N. VANCE.
